ENGINE MOUNTING

Benjamin A. Swennes, Rockford, Ill., and Rolland S. Trott, Denver, Colo.; said Swennes assignor to said Trott

Application January 21, 1933, Serial No. 652,894

16 Claims. (Cl. 248—7)

This invention relates to a power plant mounting, to a mounting unit and to a construction or method by which a plurality of the same units may be used at different points to provide substantially the entire mounting for a power plant.

The object of this invention is to provide a power plant mounting which will permit the proper independent movements of the power plant so as to prevent the transmission of engine tremor or vibration to the frame or support upon which the power plant is mounted.

A further object is to provide a mounting unit composed of a coiled spring which at all times will be under compression, combined with a rubber member which normally after being installed is under compression but which on a rebound or with over-capacity springs or before the unit is installed will be in tension.

A further object is to provide a method or construction by which the same compound mounting unit which will take both load and torque and which may be used to mount both the front and rear portions of the power plant, and may also if desired be employed as a torque connection or connections whose main duty it is to transmit torque whether a portion of the weight of the power plant is or is not supported.

All of this is described below and illustrated in the drawings, in which:

Figures 1 to 6 show different steps in the construction and installation of one form of our mounting unit, which unit will hereinafter be called a "TremoRid", a name coined for this unit which gets rid of tremor.

Figure 7 illustrates a plan view of a power plant mounted upon TremoRids at a plurality of points, all of which, or any two or more of which may be employed, as will be more fully taken up herein-after.

Figure 8 is a partial front view of the power plant shown in Figure 7.

Figure 9 is a partial section on the line 9—9 of Figure 7, looking in the direction of the arrows.

Figure 10 is a modified form of the construction illustrated in Figure 9.

Figure 11 is a partial section on the line 11—11 of Figure 7, looking in the direction of the arrows and showing an additional rubber mounting not shown in Figure 7.

Figure 12 is a modified form of the construction shown in Figure 11.

Figure 13 is a partial section on the line 13—13 of Figure 7, looking in the direction of the arrows.

Figure 14 is a sectional view of an installed

TremoRid showing a modified means of holding the end plates in place.

Figure 15 is a fragmentary plan view of one of the end plates shown in Figure 14.

Figure 16 shows another form of TremoRid construction.

Figure 17 is a fragmentary view of another form of TremoRid construction.

Figure 18 shows another form of TremoRid construction provided with safety rebound hooks. 10

Figure 19 shows another form of TremoRid construction.

Figure 20 shows another form of TremoRid construction provided with a cable as safety rebound means. 15

Figure 21 shows another form of TremoRid construction.

Figure 22 is a top view looking down on Figure 21.

Figure 23 shows another form of TremoRid construction provided with a safety rebound means. 20

Figure 24 shows another form of TremoRid construction provided with another form of safety rebound means.

Figure 25 shows another form of TremoRid 25 construction provided with another form of safety rebound means.

Figures 26 and 27 show modified forms of cups.

Figure 28 shows a modified form of adapting the TremoRid unit to a power plant mounting. 30

In Figures 1 to 6 the cups 1 are provided with the bolts 2, which may be spot-welded or otherwise prevented from turning with respect to the cups as by the rubber bonding mentioned below or in any other proper manner. The bolts 2 are 35 provided with the shoulders 3 and the threads 4. Figure 1 shows the assembled bolts and cups in their future relative positions.

The rubber member 5 is next vulcanized, bonded, cemented or otherwise properly attached to 40 form a unit with the two cups, as shown in Figure 2.

Next, the bottom plate 6 is assembled with the lower cup 1 and bolt 2 by riveting the shoulder 3 of the bolt 2 in the beveled counter bore 7 of the end plate 6. This is shown in Figure 3. The upper bolt shown in Figure 3 is a modified form having the flange 8 which is provided with two flat places 9 which will be more fully explained 45 hereinafter.

In Figure 4 it will be seen that the spring 10, which is here shown unloaded, fits snugly over the cups 1 and rubber member 5 and rests upon the lower end plate 6. 50

In Figure 5 it will be seen that the upper end plate 6 has been placed upon the spring 10 and forced downward, compressing the spring 10 so that the shoulder 3 of the upper bolt 2 may be riveted into the bevel counter bore 7 in the upper plate 6. Figure 5 therefore shows the completed TremoRid ready for installation. The rubber 5 is in tension since it alone is now resisting the extension of the spring 10 which is in compression.

Figure 6 shows the completed TremoRid of Figure 5 when it is installed between the part 11 of the power plant and part 12 of the frame with the nuts 13 and lock washers 14 properly in place. When thus installed, the weight of the engine rests upon the TremoRid and as we prefer it the rate of deflection and construction of the spring 10 is so proportioned to the load as to put normally about thirty pounds to the square inch upon the rubber member 5. It will be seen, however, that if the spring 10 is too strong or too long the rubber member 5 will carry a reversed load; that is, it will be in tension. Ordinarily, we do not prefer this construction as it means, other things being equal, the spring will not be as soft in action, and where smoothness of performance is desired we have found that the softer the spring action is, the better; provided the load on the rubber does not come to much more than thirty pounds to the square inch. However, where a TremoRid is used for a torque connection, a reversed load on the rubber in some cases is permissible depending upon conditions including the radial distance of the TremoRid from the axis of oscillation of the power plant. It will be seen that the TremoRid construction shown in Figure 5 provides a simple little unit that is entirely self-contained, that may be easily installed without the labor of compressing the spring, as shown in Figure 4, that occupies small space and may be easily stocked or shipped by mail or express.

In Figure 7 the power plant 15 is mounted upon the frame 16 by TremoRids carried by the cross members 17, 18, 19, 20 and 21. Ordinarily a power plant will be mounted upon the cross member 17 and the cross member 21, for instance, but the supports on the cross members 18, 19 and 20 may be used in place of or in addition to the support upon the cross member 21. The use of all the supports shown in Figure 7 would probably occur only under very special sets of conditions or for very special designs, weights, powers and distributions of weight in a power plant. For ordinary motor vehicle construction we prefer to support the power plant upon the cross member 17, substantially as shown, and upon the cross member 20, which, with the cross member 18 and the cross member 21, is shown broken away for the sake of clearness and to avoid confusion in the drawing. The exact longitudinal position of the cross member 20 is to be determined for any power plant by supporting the power plant as shown at the front upon a scale and moving the support at the cross member 20 back and forth longitudinally till it carries the same weight as that carried at the front. By this method both front and rear mountings, since they carry the same weight, may be constructed by the use of the same number of TremoRids of the same capacity and construction. However, due to various considerations it may be found impossible to locate the rear mounting at the point of equal weight with the front mounting and under such conditions identical weight quantities for each

TremoRid can be arrived at by variation of the angular positioning of the TremoRids. Ordinarily by this method four TremoRids, which will be interchangeable, will be sufficient to mount the entire power plant both front and rear. Under this plan, if it is necessary for weight or other considerations to use more than four TremoRids, additional TremoRids may be employed by using three or more at the front and three or more at the rear mounting, instead of 10 using additional cross members and TremoRids as shown in Figure 7.

Figure 8 shows a fragmentary front view of the construction shown in Figure 7 with the axes of the TremoRids intersecting at the desired position for the front end of the axis of oscillation of the power plant. This point of intersection may of course be changed by changing the vertical position of the TremoRids, or by changing the angle of their axes or by both changing the vertical position and the angle of their axes. The particular position of the intersection of the axes shown in Figure 8 is in the vertical plane through the axis of the crank shaft but this of course will vary with the requirements for balance in any particular power plant.

Figure 9 shows the mounting of the TremoRids on the cross member 18 and in contact with the flywheel housing 22 with the TremoRid axes intersecting at the axis of oscillation of the power plant which in this instance is illustrated as being only slightly above the axis of the crank shaft. This point of intersection may be changed by variation of the same factors mentioned regarding the construction shown in Figure 8. The construction shown in Figure 9 may either be proportioned so that the TremoRids carry some of the weight or proportioned so that the TremoRids are normally unloaded and only act to oppose the torque cushioning oscillation of the power plant.

The construction shown in Figure 10 is a variation of that shown in Figure 9 in which the axes of the TremoRids are vertical. In this construction also the TremoRids may either carry some of the weight or act solely to resiliently oppose the torque cushioning oscillation of the power plant. In the construction shown in Figure 9 and Figure 10 the TremoRid mounting may, if desired, be so designed as to put a negative load upon the TremoRids; that is, tension in the rubber member 5 will tend to pull down upon the power plant.

Figure 11 shows the construction for mounting the rear of the power plant upon the cross member 20. The mounting the rear of the power plant upon the cross member 19 is substantially the same as shown in Figure 11. The axes of the TremoRids intersect at the axis of oscillation of the power plant in both cases and the TremoRids contact the transmission 23. Ordinarily the TremoRids on both the cross member 19 and the cross member 20 will support weight, but if for any reason it is necessary or advisable, they may of course carry negative loads. Between the transmission 23 and the cross member 20 a resilient means may be provided to absorb the fore and aft movement of the power plant. The bracket 70 is bolted or otherwise properly attached to the transmission 23; the bracket 71 is bolted, riveted or otherwise properly fastened to the cross member 20, and these two brackets serve to position the rubber cushion block 72 by means of flanges as shown all around the block, or different posi-

tions may be provided by flanges on two sides of the block, flanges through the center of the block or by bonding the rubber block to members 70 and 71 or by any other proper means by which the power plant will be resiliently held against longitudinal movement.

It will be seen from the above description and from Figure 11 that the means for locating the power plant with respect to its fore and aft positions may be applied to Figures 9, 10, 12, 13, or used in connection with the front mounting on cross member 17 of Figures 7 and 8 or in any other application of this TremoRid type construction whereby full advantage may be taken 15 of the required universal movement of the TremoRid without the power plant being permitted to move longitudinally.

Figure 12 shows a variation of the construction shown in Figure 11, in which the axes of the TremoRids are vertical, and in which the TremoRids may or may not carry a load or may even have a negative load.

Figure 13 shows a construction for supporting the rear of the power plant upon the cross member 21, the TremoRids contacting the free-wheeling housing 24. A variation of this Figure 13 construction would be substantially the same as the construction shown in Figure 12. That is, the TremoRids in Figure 13 may, if desired, be positioned with their axes vertical and may be put under either a positive, a neutral or a negative load.

It will be understood from all the above that though these variations in numbers and locations of mountings and TremoRids are permissible to meet special conditions or to conform to the taste or judgment of designers, the construction for the front is substantially as shown in Figure 8 regardless of whether TremoRids are or are not used for the rear mounting. And if TremoRids are used for the rear mounting we consider it desirable that the rear mounting be so located longitudinally or the TremoRids of the rear mounting so positioned in their angularity that all TremoRids carry the same axial load and whatever the rear mounting variations may be the same size and capacity of TremoRids may be used all around, and rear constructions substantially like that shown in Figure 11 or that shown in Figure 12 may be employed.

Under some conditions it may be even advisable to use the same TremoRids and to locate them upon the cross member 21, where the weight sustained will be less than the weight sustained by the front mounting, or it may even under some conditions be advisable to locate the rear TremoRids on the cross member 19 where the weight sustained will be greater than that sustained by the front mounting. In any case we prefer that the rear mounting be so located whether on the cross member 19, 20 or 21 that the results and performance desired for the rear mounting will be provided when the same size and capacity of TremoRid is used at the rear mounting as at the front.

In the construction shown in Figure 14 the bolt 2' is provided with the flange 8 having the flat spots 9 to permit the flange to pass through the flat-sided hole 25 of the end-plate 6', which is shown also in Figure 15. If desired, the bolts 2 in Figure 5 may also have flat places to fit flat-sided holes in the end plates 6 to prevent the end plate from twisting with respect to the bolts,

and this irregular shaped bolt may be riveted the same as the round bolts shown in Figure 5. In fact, the enlarged portion of the bolts 2 which provide the shoulders 3 may be hexagonal or any other desired shape to fit a similarly shaped hole in the end plates and prevent turning of the bolts in the end plates, while the riveting prevents separation of the cups 1 and the end plates 6. After the flange 8 has passed through the plate 6' in the Figure 14 construction, the 10 plate 6' is turned so that the flat spots 9 of the flange 8 no longer align with the flat sides of the hole 25, and the end plate 6' is thereby locked in place. By this construction the TremoRid may be disassembled for replacement of the rubber member 5 if desired.

Figure 16 shows an inverted TremoRid construction in which the rubber member 26 surrounds the spring 27. The cups 28 and 29 are properly bonded to the rubber 26, and the bolt 20 30 is riveted in a beveled counter sink 31 of the cup 29. The cup 32 is also bonded to the rubber member 26 and when the TremoRid is assembled the spring 27 is placed in the cup 28 and the end plate 33, with its bolt 34 properly welded or otherwise held in place, is riveted to the cup 32 by the rivets 35, or may be attached thereto in any other proper manner.

Figure 17 shows a modified form of the construction shown in Figure 16 in which the cups 28' and 29' are bonded to the rubber member 26' and the bolt 34 is welded or otherwise properly secured to the cup 29'.

Figure 18 shows a construction similar to Figure 5 except for the addition of the safety 35 hooks 36 which are integral with the bolts 37. In case, for any reason the bonding of the rubber member 38 with the cups 39 at any time fails, the safety hooks 36 will prevent the spring 10 from completely disassembling the TremoRid.

Figure 19 shows a modification of the Figure 17 construction in which the bolt 40 is welded, riveted or otherwise properly secured to the cup 41 and the rubber member 42 is properly bonded to the cups 41 and 43 while the bolt 44 is properly welded or otherwise secured in the end plate 45. The spring 46 is properly compressed against the cup 41, and the end plate 45 is put in place and riveted there by the rivets 47, or attached thereto in any other proper manner.

While the constructions shown in Figures 16, 17, 19 and 24 all act to put the rubber members in tension before the TremoRid is installed to carry load, and under the action of torque all of this is substantially the same as the TremoRid construction shown in Figure 5, still the rubber members in Figures 16, 17, 19 and 24 do not cushion the shocks on bad road bumps in the same way as the rubber member 5 in the Figure 5 construction, for in the TremoRid shown in the Figure 5 construction the rubber, in fact, performs a triple function. It acts in compression, in tension and in torque the same as the rubber members in the Figures 16, 17, 19 and 24 constructions, but in addition to this the rubber member 65 in the Figure 5 construction, since it is a close fit in the spring 10, provides an additional and positive though resilient stop which is not provided in the construction shown in Figures 16, 17, 19 and 24.

Rubber, when confined, is noncompressible. It is deformable, but must be able to flow in order to yield. Normally, for the slight amount of cushioning required, the rubber member 5 in the Figure 5 construction may flow out to some ex- 75

tent between the coils of the spring 10, but under shock the spring 10 is compressed till its coils would be in contact and would under some conditions provide a shock or noise. But in the Figure 5 construction, as the coils of the spring 10 close together, the amount of flow permitted the rubber member 5 decreases and the rubber member becomes progressively more solid, so that before the coils of the spring 10 contact, the compressing movement will be stopped smoothly and resiliently by the increased resistance of the rubber member 5.

The construction shown in Figure 20 is similar to that shown in Figure 5, except that a cable 50 or other flexible means is pinned, welded, soldered, or otherwise properly attached to the bolts 49, which are in turn welded or otherwise properly fastened to the end cups. The cable connection 50, which is normally inactive, serves to limit the extension of the spring or extreme tension which might be put upon the rubber for any reason whatsoever, whether it be excessive rebound after installation or in the handling of the TremoRid unit before installation.

Figure 21 shows another method of construction whereby the unit can be easily assembled. The process of assembly is similar to that shown in Figure 1-4 and previously explained. In Figure 21 it will be seen that the upper plate 53 has been placed upon the spring 10 and forced downward, compressing the spring 10 so that the tongues 54 of cup 52 which at this point project straight upward, pass through the slots provided in the end plate 53, whereupon the tongues 54 are bent into the position as shown in Figures 21 and 22 and serve to contain the TremoRid as a unit. The bottom portion shown in Figure 21 is identical to the construction shown in Figure 5. However, this may be varied and both end portions may be made identical to the top as shown in Figure 21.

Figure 22 is a top view of Figure 21 and serves to show more clearly the position and the manner in which the tongues 54 are spaced about the plate 52.

Figure 23 shows a construction which in operation and effect is similar to Figure 5, except for the inclusion of a normally inactive safety rebound means. In this construction the bolt 55 is free to move in the cup 56 but which in case the bondings of the rubber member fail has a head 55' upon it whereby it will seat in the cup 56 and prevent the spring 10 from completely disassembling the TremoRid. Under the action of further compressive forces, the rubber member 5 combined with the spring 10 will stop the movement before the head of the bolt 55 is permitted to come into contact with the head of the rivet 57. The cup 56 is attached to the plate 6 by the rivets 35 or in any other proper manner.

Figure 24 shows a construction which in operation and effect is similar to Figure 16 except for the addition of a normally inactive safety rebound means, in case the bonding of the rubber member should fail. It will be seen that the cup 60 fits snugly over the spring 27. The top cup 60 is free to move in the bottom cup 61 and in case the bonding fails and the spring 27 attempts to disassemble the TremoRid, the outwardly projecting flange 64 will seat itself against the inwardly projecting flange 63 and positively limit the extension of the spring and serve to retain the TremoRid as a unit.

The construction shown in Figure 25, while similar in effect to that shown in Figure 5, is

supplemented by the addition of a safety rebound means and also as is apparent the necessity of bonding may be obviated, which is the case with any or all of the constructions shown in Figures 18, 20, 23, 24 as well as Figure 25. As will be seen from Figure 25 the upper cup 65 houses the rubber member 69 and the outwardly projecting flange 68 is free to move in the bottom cup 66. In the case of excessive rebound or if for any other reason the unit should attempt to extend beyond normal limits, the flange 68 will come into contact with the flange 67 and prevent further extension. Further the combined action of the rubber member 69 and the spring 10 will stop the movement before the upper cup flange 68 is permitted to come into contact with the lower cup 66 as a result of compressive forces. It will be noted from Figure 25 that the rubber member 69 has sufficient clearance between its outside diameter and the inside diameter of the cup 65 to permit the proper flow of the rubber under compression.

Figures 26 and 27 show cups 80 and 81 respectively to be used in the same manner as cup 1 of Figure 1. However, the cross section shape has been varied, which might afford several advantages such as greater strength, increased lateral resistance and an increased bonding area. Numerous other variations of cross sections are possible either with or without perforations therein. In all of these TremoRid constructions more or less lateral or torque resistance can be obtained by increasing or decreasing the depth of the wall section of the cups or any other proper variation that will vary the resistance of the TremoRid to lateral displacement between its two end plates. In fact, the cups may be so modified as to have no side walls whatever, in which case they would appear as flat discs, or discs with circular, radial or other indentations or proper corrugations as the case may be.

In Figure 28 will be seen a method of construction whereby a portion of the power plant weight is sustained by the centrally located TremoRid 71. The movement of the power plant about the center of oscillation is maintained by the two rubber blocks 76. The rubber blocks 76 also resiliently limit longitudinal movement of the power plant through their positioning by means of the flanges 78 of the bracket 74 and the flanges 79 of the brackets 75 and the bonding of the rubber blocks to the above brackets, or to one bracket only. The flanges 78 and 79 may be of any proper construction, as shown, or imbedded centrally in the rubber blocks, or any other proper means may be employed wherein in the bracket 74 is resiliently maintained longitudinally with respect to the brackets 75.

The above-mentioned method of mounting, while shown as being on a cross member 73, may be employed at any or all locations on the power plant as in Figure 7; that is, it may be used in conjunction with any one or all of the constructions shown on the cross members 17, 18, 19, 20 and/or 21, or in any other proper manner. The construction shown in Figure 28 shows two rubbers and one TremoRid, while the construction shown in Figure 11 shows one rubber and two TremoRids. Naturally, to suit any particular condition or requirement, any desired number of TremoRids may be used in conjunction with any desired number of rubbers to form a single mounting.

We have employed the word "TremoRid".

This is of our own coining and has been adopted as a name for the unit which is adapted to be interposed between some rigid support or foundation, such as the frame of an automobile, for example, and the object supported thereon, as for example, the power plant of an automobile, its fundamental purpose being to sustain, absorb, and dissipate the tremor or shocks incident to the activating impulses of the power plant while 5 resiliently resisting lateral displacement between its two ends. Clearances, dimensions and relative proportions of the various dimensions in any or all of these constructions are to be such as to provide the kind and amplitude of movement 10 required for any and all cases.

Having now described our invention, what we claim as new and desire to protect by Letters Patent is as follows:—

1. A weight supporting mounting for an engine 20 unit having a tendency to oscillatory movement during operation about a longitudinal axis, comprising two end members and two resilient members between the end members, one of said resilient members being metallic and the other being non-metallic, the non-metallic resilient member being fixed to the end members and limiting the extension of the metallic resilient member, each of said resilient members acting directly on the end members independently of 25 the other.

2. A weight supporting mounting for an engine unit having a tendency to oscillatory movement during operation about a longitudinal axis, comprising two end members, a rubber member limiting the separation of said end members and a compression spring between said end members and compressed during assembly so as to be in a preloaded condition.

3. A mounting unit adapted to support a load 40 and comprising a compression spring compressed during assembly so as to be in a preloaded condition and a rubber member limiting the extension of the compression spring, and means carried by the mounting unit to attach it to the load and 45 to the support therefor.

4. A mounting unit comprising two oppositely faced cups having oppositely extending threaded members, a rubber member between the cups and attached to the cups, end plates secured to the 50 cups and a compression spring compressed between the cups during assembly so as to be in a preloaded condition when assembled tending to separate said end plates and put tension on said rubber.

5. In a mounting unit to be connected to a power plant and a frame to provide for movement between the power plant and the frame and to resiliently oppose either transverse or longitudinal variation in the relative positions of its 60 two ends and composed of a coiled spring, a rubber member closely fitting within the coiled spring, end members attached to the rubber member to limit the elongation of the spring when said unit is not installed to carry load, said spring being compressed during assembly between 65 said end members and bearing thereagainst, and means at each end of said unit to attach it to the power plant and to the frame respectively.

6. A mounting unit of the character described, 70 adapted to support a load composed of two weight supporting resilient members one of which is in tension, one of said resilient members surrounding the other, means for containing said members as a unit, and means for fastening said unit

to the load to be supported and to the supporting structure thereunder.

7. A mounting unit of the character described comprising two weight supporting resilient members, one of which is normally in tension and the other is positively loaded when the unit is not installed to carry load, one of said resilient members surrounding the other, and means for containing said members.

8. A power plant mounting comprising a rubber member, cups confining opposite ends of said rubber member, a coil spring telescoped with and surrounding said rubber member with freedom of movement relative to said rubber member, and end plates separate from and connected with the cups 10 and having opposite ends of the spring bearing thereagainst, the separate end plates permitting assembly of the spring after attachment of the rubber member to the cups.

9. A power plant mounting unit comprising a 20 coiled compression spring, a non-metallic resilient member enclosed within the coiled spring, and end members connected with the spring and non-metallic resilient member, said non-metallic resilient member being constructed and arranged 25 to limit the extension of the compression spring, said spring having the coils thereof free from the non-metallic resilient member and normally disposed relatively close together under load to move closer together upon an increase in load 30 and thereby restrict flow of the non-metallic resilient member causing said last-mentioned member to carry an increased proportion of the load.

10. A power plant mounting unit comprising a 35 coiled compression spring, a rubber member enclosed within the coiled spring, separate end plates respectively attached to the rubber member and having the coiled spring bearing thereagainst, said rubber member being constructed 40 and arranged to limit the extension of the compression spring, said spring having the coils thereof free from the rubber member and normally disposed relatively close together under load to move closer together upon an increase in load 45 and thereby restrict flow of the rubber member causing said rubber member to carry an increasing proportion of the load, and means connected with the end plates for attaching the mounting unit to a load and to a support therefor.

11. A power plant mounting unit comprising telescoped resilient members, at least one of which is non-metallic, a plate at an end of the non-metallic resilient member and bonded thereto, attaching means for an end of the unit and confining the other resilient member, means for securing said attaching means to the plate after bonding of the non-metallic resilient member thereto, and means at the opposite end of said unit for confining said resilient members.

12. A power plant mounting comprising telescoped resilient members, at least one of which is non-metallic, plates at the opposite ends of the non-metallic resilient member and bonded thereto, attaching means for an end of the unit 65 having means for confining the other resilient member, means for securing said attaching means to the adjacent plate after bonding of the non-metallic resilient member thereto, and means at the opposite end of said unit for confining said 70 resilient members.

13. A power plant mounting comprising two telescoped resilient members, one being non-metallic and the other being metallic, plates at the opposite ends of the non-metallic resilient mem- 75

ber and bonded thereto, attaching means for an end of the unit having means other than the plates for confining the metallic resilient member, means for securing said attaching means to the adjacent plate after bonding of the non-metallic resilient member thereto, and means at the opposite end of said unit for confining said resilient members.

14. A power plant mounting comprising two telescopied resilient members, one being non-metallic and the other being metallic, plates at the opposite ends of the non-metallic resilient member and bonded thereto, and attaching means for the opposite ends of the unit having means other than the plates for confining the metallic resilient member, and means for securing said attaching means to the adjacent plate after bonding of the non-metallic resilient member thereto.

15. A power plant mounting comprising two telescopied resilient members, one being non-metallic and the other being metallic, the metallic member surrounding the non-metallic member, a plate at an end of the non-metallic member and bonded thereto, said plate having the periphery thereof within the inner confines of the me-

tallic member, a second plate at said end of the unit extending outwardly in position to confine an end of the metallic resilient member, means for securing said second plate to the first-mentioned plate after bonding of the non-metallic resilient member thereto, and means at the opposite end of said unit for confining said resilient members.

16. A power plant mounting comprising two telescopied resilient members, one being non-metallic and the other being metallic, the metallic member surrounding the non-metallic member, cups enclosing the ends of the non-metallic member and bonded thereto, said cups having the outer margins thereof approximately at the periphery of the non-metallic member and surrounded by the metallic member, plate members at the ends of the unit extending outwardly beyond the cups in position to confine the ends of the metallic resilient member, and for securing the plate members to the cups after bonding of the non-metallic resilient member thereto.
